UNITED STATES PATENT OFFICE.

MARY P. BEECHER, OF BRISTOL, CONNECTICUT.

COVER FOR COAL-HODS.

1,033,770.

Specification of Letters Patent. Patented July 23, 1912.

Application filed October 10, 1911. Serial No. 653,792.

To all whom it may concern:

Be it known that I, MARY P. BEECHER, a citizen of the United States, residing at Bristol, in the county of Hartford and State 5 of Connecticut, have invented new and useful Improvements in Covers for Coal-Hods, of which the following is a specification.

This invention relates to covers for coal hods or similar vessels, and has for an object to provide a cover which can be readily adjusted to an open position and held in such position when it is desired to fill the receptacle with coal or to empty the ashes therefrom.

15 In the drawing, forming a portion of this specification and in which like numerals of reference indicate similar parts in the several views:—Figure 1 is a perspective view of the coal hod showing the cover in an open position. Fig. 2 is a section on line 2—2 of Fig. 1.

The coal hod 1 herein shown may be of any suitable well known construction and configuration, and as illustrated, it is provided at the top with spaced alining ears 2. These ears are apertured, at 3, for the reception of the ends of a pintle 4. The cover 5 may be constructed of sheet metal or any other suitable material and it is preferably provided with a flange 6 which is adapted to embrace the top of the receptacle when the cover is in a closed position. At one end, the cover is curled around the pintle, as shown at 7, being soldered or otherwise secured thereto in some well known obvious manner so that on movement of the pintle the cover may be opened or closed. At one end the pintle is extended to form a small crank handle 8

which extends downwardly against one side 40 of the receptacle 1. Adjacent to the handle portion, the receptacle 1 has its walls formed to provide a locking groove 9. This groove is disposed radially with respect to the axial line of the pintle 7 and it is disposed in the path of the handle portion 8 of the pintle so as to receive the same and thereby hold the cover in an open position as shown in full lines in Fig. 1. The cover is so constructed that it provides means 50 whereby the top of the coal hod can be protected so as to prevent the escape of the ashes or the coal therefrom when carrying the hod. The cover is preferably provided with a catch 10 which is designed to engage a keeper 11 on the hod so as to hold the cover in closed position. It will of course be understood that the walls of the receptacle 1 are somewhat springy so as to permit of the effective engagement of the 55 handle 8 in the groove or the disengagement of the same therefrom.

I claim:

A coal hod, a cover therefor, a pintle soldered to one of the transverse edges of 65 the cover and pivotally engaged in the walls of the coal hod, the outer walls of the coal hod having a groove therein, and a handle formed on the pintle and adapted to engage 70 in the groove to hold the cover in an open position.

In testimony whereof I affix my signature in presence of two witnesses.

MARY P. BEECHER.
